CLAIM

The ornamental design for a taillight for a motorcycle, as shown and described.

DESCRIPTION

FIG. 1 is a perspective view of the taillight for a motorcycle. FIG. 2 is an elevational view of the side of the taillight for a motorcycle.

FIG. 3 is an elevational view of the opposite side of the taillight for a motorcycle shown in FIG. 2.

FIG. 4 is an elevational view of the front end of the taillight for a motorcycle.

FIG. 5 is an elevational view of the back end of the taillight for a motorcycle shown in FIG. 4.

FIG. 6 is top plane view of the taillight for a motorcycle; and,

FIG. 7 is a bottom plane view of the taillight for a motorcycle.
